DESIGN FOR A WATCHCASE

Alexander Herbst, Jackson Heights, N. Y., assignor to Robert C. Barnstone, New York, N. Y.

Application July 8, 1936, Serial No. 63,709

Term of patent 3½ years

To all whom it may concern:

Be it known that I, Alexander Herbst, a citizen of the United States and a resident of the city of New York, in the county of Queens and State of New York, whose post office address is 3740 81st Street, Jackson Heights, city and State of New York, have invented a new, original, and ornamental Design for a Watchcase, of which the following is a specification, reference being had to the accompanying drawing, forming part thereof:

Fig. 1 is a face view of the watch, showing my new design;

Fig. 2 is a view of the back of the watchcase shown in Fig. 1;

Fig. 3 is a side elevational view of the watchcase shown in Fig. 1, and

Fig. 4 is an end elevational view of the watchcase shown in Fig. 1.

I claim:

The ornamental design for a watchcase substantially as shown.

In testimony whereof, I have hereunto subscribed my name this 7th day of July 1936.

ALEXANDER HERBST.
